UNITED STATES PATENT OFFICE.

RALPH H. BINNS, OF PITTSBURGH, PENNSYLVANIA, AND WILLIAM A. DE HART, OF TEANECK, NEW JERSEY, ASSIGNORS TO EDWARD H. BINNS AND RALPH H. BINNS, BOTH OF PITTSBURGH, PENNSYLVANIA.

FLEXIBLE CLOSURE.

Application filed February 28, 1925. Serial No. 12,449.

The present invention relates to improvements in pull members and locking devices for cam sliders of the type employed with flexible strips or stringers of spaced interlocking fastening devices. The present invention may be considered as an improvement upon the device covered by the application of Ralph H. Binns, filed February 18th, 1925, Serial No. 10,074. 10 The pull member of the present application utilizes the leverage control of the operating slider set forth in said Binns application, but extends the application of this principle to a more effective angular control of the slider in both its locking and unlocking movements. This is accomplished by mounting the pull pin approximately centrally of the slider body and arranging a reversible pull member in the form of a blade of spring metal capable of movement from a central position beneath said pull pin to extend either above or below the slider body. The opposite ends of the pull member are so designed that 20 a slight outward stress upon the outwardly presented end of the pull member in addition to the pull in the desired direction will bring into action a fulcrum heel for controlling the angular position of the slider upon the interlocking fastening devices. This improved flexible closure may also include a modification of the slider lock in the form of a frictional drag or brake under the control of manually operated means such as the pull member. An improved form of stop upon the stringers is also provided for limiting the locking movement of the slider upon the fastening devices. 30 In order that the invention may be fully understood it will first be described with reference to the accompanying drawings and afterwards more particularly pointed out in the annexed claims.

In said drawings:

Fig. 1 is a front elevation of a portion of a flexible closure embodying the present invention;

Fig. 2 is a side elevation of the same; 50 Fig. 3 is a similar view, partly in section, showing the pull member extended below the slider;

Fig. 4 is a similar view showing the pull member extended above the slider;

Fig. 5 is a rear view of the slider; 55

Fig. 6 is a transverse sectional view taken on the line 6—6 of Fig. 1;

Fig. 7 is a view similar to Fig. 6 showing the locking drag or brake raised away from the locking devices; and 60

Fig. 8 is a detail perspective view of the slider limiting stop.

In the type of flexible closure to which the present invention relates, two flexible strips or stringers 1, 2 are formed at their inner edges with beads or thickened portions 3 upon which are secured interlocking fastening devices. 65

Each interlocking fastening device is preferably formed with a U-shaped yoke 10 70 embracing and compressed upon the beaded or thickened edge 3 of a flexible stringer, a narrow neck 12, a forked hook 13, and the opposite riding lugs or shoulders 15. The specific form and operation of the fastening devices of the preferred construction will be more fully understood by reference to the application of Binns, Binns and De Hart, filed July 5th, 1924, Serial No. 724,355. 75

The operating cam slider is preferably constructed, as set forth in the above named application, of a back-plate 20 and a fore-plate 21 mounted in spaced relation upon a binder post (not shown), to provide a fastener receiving channel. The inner faces of the back-plate and fore-plate are provided with controlling grooves 25 separated by a central guide rib or surface 26. The riding lugs 15 of the fastening devices operate in 80 the controlling grooves 25.

The fore-plate 21 of the slider body is provided approximately midway between its upper and lower ends with the outwardly presented ears or lugs 30 carrying a transverse pivot and pull pin 35. 85

At the upper end of at least one series of interlocking members, is provided a stop lug 27 formed on the yoke 28 and having its two arms integrally connected with the 100 arms of a yoke 10^a through the web portions 29. The yoke 10^a is part of a specially formed fastening member having a narrow neck 12^a, a forked hook 13^a and the riding

lugs or shoulders 15^a. The connections 29 between the yokes 28 and 10^a (which are clamped upon the beaded edge of a stringer) mutually and effectively brace the 5 top fastening member and stop lug to lessen the liability of misplacement from strains.

It will be understood that in the closing operation of the slider upon the fastening devices, one of the ears 30 will come into 10 engagement with stop lug 27 and limit the movement of the slider. The stop lug 27 is so mounted that it will pass outside of and along one edge of the slider in this closing movement.

15 The U-shaped drag or brake member 40 is freely pivoted upon the pin 35 and shaped to fit over the lower end of slider fore-plate 21. The portions of the drag or brake 40, which are presented toward the exposed 20 faces of the interlocking fastening devices, are suitably shaped to frictionally engage the fastening devices for securing the slider in the desired position thereon. As shown 25 this member 40 is formed with a central braking surface 41 designed to engage the edges of adjacent interlocked fastening devices, and side braking surfaces 41^a to engage the locking devices adjacent riding lugs or shoulders 15.

30 50 is a blade-like pull member movably mounted upon the slider beneath the pivot and pull pin 35. This pull member 50 is made of spring metal and is formed with a slight arch or bow shape to cause it to effectively though yieldingly engage the pin 35. Pull member 50 has a central transverse bend or recess 51 which snugly engages pin 35 in its central locked position as shown 35 in Figs. 1 and 2. The opposite ends of pull member 50 are slightly rolled or coiled to form finger pieces 52 and 53, which also act as fulcrum heels for engaging the face of top plate 21 and giving a leverage control of the angular position of the slider when it is 40 moved upon the fastening devices.

The devices are shown in normal locked 50 position in Figs. 1, 2 and 6 of the drawings, in which position the pull member 50 is sprung beneath the pin 35 with its upper end frictionally engaging the upper central portion of the fore-plate of the slider and its lower end resting upon the drag or brake 40 and holding it in locked engagement with the interlocked fastening devices. In this 55 position stop lug 27 is in engagement with ear 30 of the slider. The slider is held against movement in either direction. To open the closure the pull member 50 is shifted into the position shown in Fig. 3 of the 60 drawings to project below the slider and release the drag or brake 40. In this position by slight outward pressure in the direction of arrow *x*, combined with a downward pull in the direction of arrow *y*, the fulcrum heel 52 will afford sufficient leverage control 65

of the angular position of the slider to prevent "digging in" at the downward or leading end, and cause the slider to move freely upon the fastening devices to move them into unlocked position.

70

When it is desired to fasten the closure, the pull member 50 is moved into the position shown in Fig. 4 in which outward pressure in the direction indicated by arrow *x'*, combined with the pull in the direction of 75 arrow *y'* causes the slider to move freely over the fastening devices to interlock them without any tendency to bind or catch upon them.

80

We claim:

1. In a flexible closure or fastener, the combination of flexible strips or stringers having spaced interlocking fastening devices, and a slider embracing and sliding upon said fastening devices for interlocking and unlocking them, with a pull pin mounted transversely upon said slider approximately midway between the slider ends, and a pull member movably engaging said pin and having means for limiting the angular movement of said pull member thereon.

35

2. In a flexible closure or fastener, the combination of flexible strips or stringers having spaced interlocking fastening devices, and a slider embracing and sliding upon said fastening devices for interlocking and unlocking them, with an angularly movable pull member shiftably mounted upon said slider between the ends of the slider, said pull member having means at both ends for 90 limiting the angular movement of the pull member upon the slider.

95

3. In a flexible closure or fastener, the combination of flexible strips or stringers having spaced interlocking fastening devices, and a slider embracing and sliding upon said fastening devices for interlocking and unlocking them, a pin mounted upon said slider between the slider ends, with a shiftable pull member movably mounted upon said slider beneath said pin and having at its opposite ends means for engagement with said pin.

100

4. In a flexible closure or fastener, the combination of flexible strips or stringers having spaced interlocking fastening devices, and a slider embracing and sliding upon said fastening devices for interlocking and unlocking them, said slider carrying a pull pin spaced from it between its ends, with a blade-like pull member movably mounted upon said slider beneath said pin and having limiting stops at its opposite ends to engage said pull pin and limit the lengthwise and angular movements of said pull member.

105

5. In a flexible closure or fastener, the combination of flexible strips or stringers having spaced interlocking fastening devices, and a slider embracing and sliding upon said fastening devices for interlocking and unlocking them, said slider carrying a pull 110

115

120

125

130

pin spaced from it between its ends, with a blade-like pull member movably mounted upon said slider beneath said pin and having a central groove or recess normally engaging said pull pin to hold the pull member in central position, said pull member also having limiting stops at its opposite ends to engage said pull pin and limit the lengthwise and angular movements of said pull member.

6. In a flexible closure or fastener, the combination of flexible strips or stringers having spaced interlocking fastening devices, and a slider embracing and sliding upon said fastening devices for interlocking and unlocking them, said slider having a pull pin mounted upon it between its ends, with a pull member movably mounted upon said slider beneath said pin, said pull member being in the form of a blade of spring metal having a central groove or recess to engage said pull pin and hold said pull member in central position upon the slider, and said pull member also having at its opposite ends means for engagement with said pull pin.

7. In a flexible closure or fastener, the combination of flexible strips or stringers having spaced interlocking fastening devices, and a slider embracing and sliding upon said fastening devices for interlocking and unlocking them, with a drag or brake pivotally mounted upon said slider and engaging said fastening devices, and a manually operated device movably mounted upon said slider in position to engage and control said drag or brake.

8. In a flexible closure or fastener, the combination of flexible strips or stringers having spaced interlocking fastening devices, and a slider embracing and sliding upon said fastening devices for interlocking and unlocking them, with a pull member having limited movement upon said slider, and a drag or brake pivotally mounted upon said slider and held in engagement with said fastening devices by said pull member.

9. In a flexible closure or fastener, the combination of flexible strips or stringers having spaced interlocking fastening devices, and a slider embracing and sliding upon said fastening devices, for interlocking and unlocking them, with a pull pin mounted upon said slider, a pull member shiftably mounted between said pin and said slider, said pull member being angularly movable upon said pin and having means at both ends for limiting its angular movement upon the slider, and a drag or brake pivotally mounted upon said pin and normally held by said pull member in engagement with said fastening devices.

10. In a flexible closure or fastener, the combination of flexible strips or stringers having spaced interlocking fastening devices, and a slider embracing and sliding

upon said fastening devices for interlocking and unlocking them, with a U-shaped drag or brake pivotally mounted upon said slider and extending beyond one end thereof and engaging said fastening devices, and a pull member movably mounted upon said slider and normally engaging said drag or brake.

11. In a flexible closure or fastener, the combination of flexible strips or stringers having spaced interlocking fastening devices, and a slider embracing and sliding upon said fastening devices for interlocking and unlocking them, said slider carrying a pull pin spaced from it between its ends, with a blade-like pull member mounted to move longitudinally and angularly upon said slider between the pull pin and the slider, said pull member having means at both ends for limiting the lengthwise and angular movements of the pull member upon the slider, and a locking drag or brake pivotally mounted upon said pull pin and held normally in engagement with said fastening devices by said pull member.

12. In a flexible closure or fastener, the combination of flexible strips or stringers having spaced interlocking fastening devices, and a slider embracing and sliding upon said fastening devices for interlocking and unlocking them, said slider carrying a pull pin spaced from it between its ends, with a shiftable blade-like pull member movably mounted upon said slider beneath and in engagement with said pull pin, said pull member having a recess between its ends for engagement with said pull pin and means at both ends for limiting the lengthwise and angular movements of the pull member upon the slider, and a locking drag or brake pivotally mounted upon said pull pin and held normally in engagement with said fastening devices by said pull member.

13. In a flexible closure or fastener, the combination of flexible strips or stringers having spaced interlocking fastening devices, and an operating slider embracing and sliding upon said fastening devices, with a slider stop secured to one of said strips or stringers and rigidly attached to and braced by one of said fastening devices.

14. In a flexible closure or fastener, the combination of flexible strips or stringers having spaced interlocking fastening devices, and an operating slider embracing and sliding upon said fastening devices, with a U-shaped yoke embracing and clamped upon the edge of one of said strips or stringers, a stop lug upon said yoke arranged to engage and arrest said slider, and a web portion extending from said stop lug yoke and connected to one of said fastening devices.

15. In a flexible closure or fastener, the combination of flexible strips or stringers having spaced interlocking fastening de-

5 vices, and an operating slider embracing and sliding upon said fastening devices, with a slider stop member spaced from and integrally connected with one of said fastening devices.

16. In a flexible closure or fastener, the combination of flexible strips or stringers having spaced interlocking fastening de-

10 vices, and an operating slider embracing and sliding upon said fastening devices, 10 a pair of integrally connected yokes embracing and clamped upon the edge of one of said strips or stringers, one of said fastening devices being mounted upon one of said yokes, and a slider stop lug upon the 15 other of said yokes.
